CURTAIN MOUNTING

Filed April 22, 1927

INVENTOR
EMIL ZUCCA
BY Walton Harrison
ATTORNEY

UNITED STATES PATENT OFFICE

EMIL ZUCCA, OF NEW YORK, N. Y.

CURTAIN MOUNTING

Application filed April 22, 1927. Serial No. 185,674.

My invention relates to curtain mountings, and admits of general use upon curtains of many different kinds and employed in various relations throughout many different arts.

More particularly stated I seek to produce a curtain mounting for so supporting a curtain as to enable the latter to be adjusted easily by hand and yet to maintain the curtain as nearly as practicable air tight. 5
10 My invention further comprehends giving to the curtain and the means for mounting the same, such form as to greatly improve the efficiency of the curtain, and to accomplish a number of other purposes, all as hereinafter 15 more particularly described, and pointed out in the appended claims.

Reference is made to the accompanying drawing forming a part of this specification, and in which like reference characters indicate like parts throughout all of the figures.

Figure 1 is a front elevation of my improved curtain mounting, adapted in this instance for use upon a window, certain parts being broken away and others shown in section, as the curtain mounting is seen by a person standing in the room and looking toward the window. 25

Figure 2 is a section on the line 2—2 of Figure 1, looking in the direction indicated 30 by the arrows.

Figure 3 is a section on the line 3—3 of Figure 1, looking in the direction indicated by the arrows.

Figure 4 is a front view, partly in section 35 and partly in elevation, showing in detail certain parts which appear in Figure 1, the scale of Figure 4 being somewhat larger.

A curtain 5, which is flexible and practically opaque to light, is at one of its ends 40 connected with a roller 6, and so arranged as to be readily wound upon and unwound from said roller.

The roller 6 is preferably of the type known generally in this art as a Hartshorn shade 45 roller. I do not deem it necessary to describe

this roller further than to say that the curtain hangs from it and is unwound by pulling downwardly upon the lower end of the curtain, and is wound up by the automatic rotation of the roller, which is always under 50 spring tension. In practice the operator merely grasps the lower portion of the curtain and pulls it downward in order to unwind the curtain. In order to cause the curtain to be wound up he gives its lower end a 55 slight jerk downward, and then quickly raises the lower end of the curtain to the height desired for it, the slack of the curtain being taken up automatically by the rotation of the roller, as above stated. 60

The portion of the curtain taken up by the roller and thus wound around the same, is shown at 7.

The roller 6 is supported upon bearings 8, 9, which are mounted oppositely to each other 65 in a roller casing 10.

The roller casing 10 is provided with a door 11 mounted upon hinges 12. By opening this door, access may be had to the roller and other parts housed within the roller casing. 70

The curtain 5 is at its lower end provided with a portion 13, bent back upon itself and provided at 14 with stitches, being thus formed into a sleeve. Extending through 75 this sleeve is a bar 15 made preferably of wood, and also a tube 16, made preferably of metal and rather heavy.

A curtain rod 17, having a length a little greater than the width of the curtain, extends entirely through the tube 16. This curtain rod carries at its ends a pair of metallic knobs 18, 18, each of substantially spherical form. 80

By means of stitches 19 the material of the curtain is drawn rather closely around the adjacent portions of the curtain rod, and is thereby formed into two neck portions 20, 20, fitting closely around the curtain rod, as indicated in Figures 3 and 4. 85 90

I provide four jamb pieces 21, 22, 23 and 24, and arrange them as indicated in Figure 3. The jamb pieces 21 and 22 are secured together and thus made practically into a single piece. Similarly the jamb pieces 23 and 24 are secured together, and may be considered as essentially one piece. A connecting strip 26 is secured to the jamb pieces 21 and 22, and a connecting strip 27 is secured to the jamb pieces 23 and 24.

Thus are formed two complete jambs of composite form, these two jambs being designated respectively as 28 and 29, as indicated more particularly in Figure 3.

The two jambs just mentioned are each provided with a slot 30 having an enlarged portion 31 in the form of a substantially cylindrical hole into which the slot 30 is merged.

The metallic knobs 18, 18, are fitted slidably into the enlarged portion 31 of the slots 30, and the edges of the curtain 5 extend out into the slots 30. For this purpose the width of the curtain is somewhat greater than the distance between the two jambs. The idea is that the edges of the curtain shall extend out far enough into the respective jambs to prevent wind from blowing around the edges of the curtain, and to render the latter as nearly as practicable dust proof.

Screws 25 or equivalent fastenings are used for holding together various wooden parts constituting the two jambs.

The two jambs are provided with a pair of rounded shoulders, exactly alike, one of them being shown at 32, in Figure 2. The purpose of these rounded shoulders is to guide the curtain 5 in its movements.

My improved curtain mounting in its entirety may be fitted upon a pair of window jambs 33, 33, as indicated in Figure 1, or it may be fitted into any sort of opening used as a window or a door. It may be used upon houses, railroad cars, automobiles, refrigerators, and in various relations upon ships, boats and other vessels. In fact my device may be employed upon or within almost any kind of a structure upon which an adjustable curtain is desirable.

The operation of my device may be understood from the foregoing description. The various parts being formed and arranged as shown, the device is ready for use.

The operator, in order to raise or lower the curtain, proceeds in the same manner as he would to raise or lower any other curtain mounted upon a spring roller of the general type here contemplated.

Neither the curtain nor any movable part connected with it can readily be dislodged or misplaced by action of the wind, or by any sort of accidental disturbance. If the wind blows against the curtain, the curtain does not flex, buckle, bend or become distorted to any appreciable extent, the action of the wind being resisted in much the same manner as it

would be by a pane of glass. Thus the wind cannot blow around the edges of the curtain, the curtain cannot rattle or become noisy, and it stays firmly in whatever position it is moved into, from time to time, by the operator. The knobs 18, 18, being always the same distance apart, cannot pull sidewise upon the curtain, and any tendency of one of these knobs to pull the curtain sidewise is balanced by the similar but contrary tendency of the other knob. Such being the case, it follows that each edge of the curtain extends to the same distance into the adjacent jamb as the opposite edge of the curtain extends into the opposite jamb. It also follows that the knobs so coact with the jambs as to prevent the edges of the curtain from being withdrawn from the slots.

The weight of the curtain rod 17 and the two knobs 18, 18, together with the weight of the metallic tube 16, and wooden bar 15, is adequate to keep the curtain taut at all times and under all conditions.

I do not limit myself to the precise construction shown, as variations may be made therein without departing from my invention, the scope of which is commensurate with my claims.

Having thus described my invention, what I claim as new and desire to secure by Letters Patent is as follows:

1. In a curtain mounting the combination of a pair of jambs provided with slots, said slots extending into said jambs and having enlarged portions therein, a curtain rod extending across from one jamb to the other and reaching into said slots of said jambs, said curtain rod being provided at its ends with enlarged portions fitting into said enlarged portions of said slots, a curtain movable relatively to said jambs and provided with edge portions extending into said slots and slideable therein as said curtain is moved relatively to said jambs, and a tubular member encircling said curtain rod and carried therewith by said curtain, said tubular member having a length less than the width of said curtain, the edge portions of said curtain, where they reach into the slots of said jambs, extending beyond the ends of said tubular member.

2. In a curtain mounting the combination, with a pair of jambs having slots, a curtain movable relatively to said jambs and extending well into said slots, and a curtain rod carried by said curtain and extending into said slots, of a tubular member encircling said curtain rod and therewith carried by said curtain, the length of said tubular member being less than the distance between said jambs.

3. In a curtain mounting the combination, with a pair of jambs having slots and a curtain movable relatively to said jambs and having edge portions extending into said

slots, of a curtain rod carried by said curtain and extending into said slots, of a tubular member and a bar carried by said curtain rod, and each having a length less than the width of said curtain and less than the distance between said jambs, said curtain being bent back upon itself so as to encircle said bar and said tubular member, and secured by stitching.

10 Signed at New York city, in the county of New York and State of New York, this 21st day of April, 1927.

EMIL ZUCCA.
